ABRADING TOOL

William Roderick Barclay, Leicester, England,
assignor to United Shoe Machinery Corporation,
Paterson, N. J., a corporation of New Jersey

Application December 4, 1934, Serial No. 755,972
In Great Britain June 5, 1934

5 Claims. (Cl. 51—194)

This invention relates to abrading tools and is herein disclosed as embodied in a disk type of tool such as is used in buffing the shank and heel breasts of shoes. In the application for United States Letters Patent of Fred Ricks and Ernest Hope, Serial No. 755,962, filed December 4, 1934, there is disclosed a disk type of tool wherein the abrasive element is supported upon an inflatable ring. The abrasive element of that tool consists of a strip of abrasive sheet material molded to conform to the periphery of the supporting ring. The ends of the abrasive strip are adhesively secured together in overlapping relation, and the expansion of the ring by air pressure holds the abrasive element in place. The tool disclosed in the present application is similar in the respects above mentioned to the tool disclosed in the application of Ricks and Hope.

It is an object of the present invention to provide an improved abrading tool of the character under consideration. In accordance with a feature of the invention, the expandable ring is recessed at the lapped joint of the abrasive element to avoid undue bulkiness at this locality. In the illustrated tool the outer wall of the expandable ring is of substantially the same thickness at the recess as at the other portions of the ring in order to prevent bulging of the ring at this locality when expanded by air pressure. In accordance with a further feature, the expandable ring has a gritty surface to prevent slip between the abrasive element and the ring in order to insure that the lapped joint of the abrasive element will always be in register with the recess in the expandable ring. The gritty surface of the ring is obtained by incorporating particles of friction-producing material, for example flint, in the peripheral surface portion of the ring prior to treatment of the ring in a vulcanizing mold. The increased frictional characteristics of the ring resulting from such treatment are sufficient to overcome any tendency of the abrasive element to creep, which might otherwise result from the frictional drag of the work upon the abrasive element.

With the above and other objects and features in view, the invention will now be described with reference to the accompanying drawing and pointed out in the claims.

50 In the drawing,

Fig. 1 is an elevational view, partly in section, of the improved tool in operation upon the breast surface of the shoe heel;

55 Fig. 2 is a view in perspective of an inflatable

pad for supporting an abrasive cover upon the above-mentioned tool;

Fig. 3 is a sectional view taken on the line III—III of Fig. 2;

Fig. 4 is a sectional view taken on the line IV—IV of Fig. 2;

Fig. 5 is a perspective view of the abrasive element used on the tool; and

Fig. 6 is a view showing a joint in the abrasive element.

Referring to Fig. 1, the illustrated tool is shown in operation upon the breast surface of a heel H of a shoe S. As illustrated, the tool is supported upon the tapered end of a tubular spindle 10 which is driven by any suitable means. The tool comprises a body portion in the form of a wheel 12 which is conveniently made of aluminum and which has a hub 14 in which is formed a socket for receiving the end of the spindle 10. The tool body 12 is of general discoidal form but its central portion is somewhat convex toward the spindle 10. Slidably fitted over the hub 14 is a hub of a clamping member 16 of substantially the same diameter as the tool body 12. The periphery of the tool body 12 is recessed and the tool body 12 and the clamping member 16 have flanges 18 and 20, respectively, formed thereon. A nut 22 is threaded upon the hub 14 in abutting relation to the hub of the clamping member 16.

Mounted upon the periphery of the tool body 12 is an inflatable ring 24 of rubber. This ring is shown in perspective in Fig. 2, and the form of its radial section is shown in Fig. 4. At the base of the ring there extends inwardly a tongue 26 by which the ring is clamped between the disk 16 and the tool body 12. The spindle 10 has an axial passageway 28 which, at its upper end, is connected with any suitable source of air under pressure. A small tube 30 opens at one end into the socket of the hub 14 and at its other end extends slightly beyond the surface of the recessed peripheral portion of the tool body 12. When the inflatable ring 24 is assembled in position upon the tool body, a small opening through the tongue 26 of the ring registers with the projecting end of the tube 30 to form an air tight joint. The ring 24 is provided with an annular air chamber 32 which communicates with the above-mentioned opening in the tongue 26. Air under pressure will thus pass from the passageway 28 into the socket of the hub 14, thence through the tube 30 and the opening in the tongue 26 into the air chamber 32 to inflate the ring 24. As is shown in Fig. 4, the wall of the air chamber 32 is thinner at the peripheral portion of the

50 55

ring than at its sides, in order that the air under pressure being introduced into the ring will cause the expansion of the ring to take place diametrically rather than transversely. The ring 24 may 5 conveniently be made by vulcanizing together two suitable pieces of rubber in a mold, and as shown in Figs. 3 and 4, a strip 34 of canvas may be introduced at the joint at the base to strengthen the ring.

10 As shown in Figs. 1, 5 and 6, the abrasive element of the tool consists of an annular cover 36 of abrasive sheet material. The abrasive cover 36 has an inherent shape which is similar to that of the periphery of the ring 24. This shape may 15 conveniently be obtained by a molding operation which is illustrated and described in the above-mentioned application of Ricks and Hope. The cover is applied to the tool when the ring 24 is in deflated condition, an overlapping end of the 20 cover being cemented to an underlapping end.

As so far described, the abrading tool, including the abrasive cover 36 is similar to the tool disclosed in the above-mentioned application of Ricks and Hope. In the present construction, 25 however, the tongue 26 is not of dove-tail formation but is provided with annular recesses 38, 39 at its base to accommodate the flanges 18 and 20 of the tool body and clamping disk, respectively. As shown in Fig. 6, the overlapping end 37 of 30 the abrasive cover 36 in forming the joint is of a re-entrant V-shaped outline so that the joint is of greater extent at the sides than at the center of the cover. In the ordinary use of tools of this character, the side surfaces of the abrasive cover 35 are used more than the central portion and this form of joint gives added strength at the localities where strength is most required, without rendering the joint unduly bulky. The abrasive material need not be removed from the end portions 40 of the cover 36 at the point and is preferably retained at least upon the overlapping end.

The surface portion of the ring 24 which underlies the abrasive cover has incorporated in it particles of grit to increase its frictional characteristics. This is accomplished by sprinkling minute 45 particles of grit, for example flint, upon the surface of the ring prior to the treatment of the ring in a vulcanizing mold.

As shown in Fig. 2 the inflatable ring 24 has a 50 recessed portion 40 in its peripheral surface. Fig. 3 represents a cross section of the ring taken through this recessed portion. The recessed portion is of a length somewhat in excess of the length of that joint of the abrasive cover. The 55 depth of the recess is substantially equal to or slightly in excess of the thickness of the abrasive sheet material from which the covers are made, and the recess at each end terminates in a shoulder 42 which conveniently is not perpendicular to the adjacent surface but is inclined at an angle of about 45°. In order to prevent the absence of material at the recessed portion 60 40 from causing undue inflation of the ring at

that locality, the ring is so formed that the annular air chamber 32 at the recessed portion is displaced inwardly toward the center of the ring a distance corresponding to the depth of the recess. Thus, as appears from the comparison 5 of Figs. 3 and 4, the same amount of material is left between the peripheral surface of the ring and the annular air chamber, both at the recessed portion 40 and at the remaining portions of the ring, and uneven inflation is thereby prevented. 10

The abrasive cover 36 is applied upon the ring 24 when the latter is in deflated condition. The ends of the abrasive cover are cemented together in overlapping relation at the locality of the 15 recess 40. When air pressure is admitted into the hollow 32, the expansion of the ring will hold the abrasive cover in place, and the gritty surface of the ring will prevent any tendency on the part of the abrasive cover to creep in such a manner 20 as to move the joint away from the recess 40. The recess 40 insures an even surface of the abrasive cover notwithstanding the joint.

Having described the invention, what is claimed as new and desired to be secured by Letters Patent 25 of the United States is:

1. An abrading tool comprising a supporting member and a cover of abrasive sheet material mounted upon said supporting member, said abrasive cover having its ends adhesively secured together to form a lapped joint, and said supporting member being recessed at the locality of the joint to prevent undue bulkiness at that locality. 30

2. An abrading tool comprising an expandable pad, and an annular abrasive cover carried by said pad and retained upon said pad by the expansive pressure of the latter, said abrasive cover having a lapped joint, and said pad having a recess to accommodate said lapped joint. 35

3. An abrading tool comprising an inflatable pad adapted to carry an abrasive cover and having a recess in its cover-supporting surface to accommodate a lapped joint in the abrasive cover. 40

4. An abrading tool comprising an inflatable pad having an outer surface adapted to carry an abrasive cover and having a recess in its outer surface to accommodate a lapped joint in the abrasive cover, the outer wall of said pad being of substantially the same thickness at said recess as at other portions of said pad. 45

5. An abrading tool comprising an annular inflatable pad, and an annular abrasive cover carried by said pad and retained upon said pad by the expansive pressure of the pad when the latter is inflated, said abrasive cover having a lapped joint, and said pad having a recess to accommodate said lapped joint, said pad having also particles of gritty material incorporated in its cover-supporting surface to prevent relative slip between the pad and the cover and thereby to 60 keep the lapped joint in register with the recess. 55

WILLIAM RODERICK BARCLAY.
